(57) CLAIM

The ornamental design for a handle for cookware, as shown and described.

DESCRIPTION

FIG. 1 is an enlarged upper perspective view of the handle for cookware showing my new design.

FIG. 2 is front elevation view thereof;

FIG. 3 is a rear elevation view thereof;

FIG. 4 is a top plan view thereof;

FIG. 5 is a bottom plan view thereof;

FIG. 6 is a side view thereof; and,

FIG. 7 is an opposite side view thereof.

The features presented in broken lines are for environmental purposes only and form no part of the claimed design.
